(57) **CLAIM**

The ornamental design for a fish gripping and measuring device, as shown and described.

DESCRIPTION

The ornamental design, as herein set forth, is not related to any federally sponsored research or development.

FIG. 1 is a perspective view of the ornamental design for a fish measuring device, according to the principles of the invention.

FIG. 2 is a plan view showing the top side of the ornamental design for a fish measuring device.

FIG. 3 is a plan view showing the bottom side of the ornamental design for the fish measuring device; and, FIGS. 4 and 5 show respective side views of the ornamental design for a fish measuring device.
